STACKED HEAT INTERCHANGER
 Lyle D. Guthrie, 1619 Guy St., Apt. 3, San Diego, Calif.
 Filed Mar. 27, 1961, Ser. No. 98,534
 4 Claims. (Cl. 165—108)

This invention relates to a heat exchanger, and more particularly to a heat exchanger of the stacked heat-interchanger type.

Background

One of the most satisfactory methods of heating fluids is to use the hot gases resulting from combustion, and to extract heat therefrom and transfer the heat to the fluid by means of heat-interchangers.

Since the results of combustion are hot gases, and the fluids to be heated may be either liquids or gases, the following terminology will be used for clarity of explanation. The hot gases will be called "flue gases," and the fluid to be heated will be called "water." These terms however, should not be construed as meaning that my invention is limited to the heating of water.

Heat exchangers inherently have a number of problems. Among these are the tendency for water vapor in the flue gas to produce corrosive action. Another problem stems from the necessity of obtaining the maximum amount of heat from the gases before they escape up the flue. This latter problem requires that the heat interchangers have a large area, so that they are exposed to a large volume of hot flue gases, and can quickly extract a large amount of heat therefrom.

If however, a series of heat exchangers are sequentially presented to the flue gases, the cooled gases transfer only a small amount of heat to the rearmost heat interchangers.

Objects and drawings

It is therefore the principal object of my invention to provide an improved heat exchanger.

It is another object of my invention to provide a novel heat exchanger having a plurality of stacked small-area heat interchangers.

It is further an object of my invention to provide an improved heat interchanger that extracts substantially the same amount of heat from the flue gases, even though the gases are relatively cooler when they pass the rearmost heat interchangers.

It is still another object of my invention to provide an improved, novel heat exchanger that is extremely efficient and easy to assemble.

The attainment of these objects and others will be realized from the following specification taken in conjunction with the drawings, of which—

FIGURE 1 shows my basic inventive concept; and FIGURES 2-4 show cross sections of the heat interchangers used therein.

Broadly speaking, my invention contemplates a heat exchanger comprising three substantially concentric tanks. The water to be heated is contained in the innermost heated tank and in the outermost storage tank, while the heating gases pass through the intermediate heater chamber. Heat interchangers are placed in the heater chamber in a stacked manner to sequentially extract heat from the flue gases, and to transmit the extracted heat to both the heated chamber and to the storage chamber. The sequentially positioned heat interchangers have vanes with vane areas becoming progressively larger as the flue gases become progressively cooler. This progression of vane areas provides more efficient heat extraction from the progressively cooler flue gases.

It will be realized from the following description of my invention, that the disclosed heat interchangers have a greater capability for heat extraction from the cooler

2

portions of the flue gases. This tends to equalize the quantity of heat transfer, that is the actual B.t.u. transfer, and therefore tends to equalize temperatures along the length of the stacked assembly, particularly at the junction of the heat interchanger and the heated chamber. This results in decreased stresses, and therefore longer useful life for the equipment.

The invention

10 In the heat exchanger 10 of FIGURE 1, cold water flows through inlet pipe 12 into storage chamber 14. This comprises a tank of any desired configuration, wherein walls 16 have suitable construction and thermal insulative properties. If desired, a composite wall of strong material and an insulating liner may be used.

15 The cold water at the bottom of storage tank 14 flows as shown by arrow 18, and enters the innermost heated chamber 20. The heated chamber is formed by a pipe 22, through which the water flows upwards as it is heated. (The heating process will be described later in greater detail.) The heated water emerges from the top of heated chamber 20 as shown by arrow 24, and enters storage chamber 14.

20 As the heated water enters the top of the storage chamber, it may be withdrawn through the hot water outlet 26 as needed. While the illustration shows the heated water to rise through the heated chamber and pass into the storage chamber by convection and gravity flow, my invention will also operate in a horizontal position, although a pump may then be required.

25 In order to heat the water, fuel gas flows through fuel line 28 at the bottom of the heat exchanger, and enters burner 30. Here the fuel gas is burned, and the hot gases of combustion flow upwards through the heating chamber 32 formed by walls 33 and pipe 22, and out of the flue 34. While a gas burner 30 is shown, it may of course be replaced by an oil burner, electric heater, steam, or any other source of heat.

30 As the hot flue gases travel along heating chamber 32, it is necessary to extract the heat from them and to transfer the extracted heat to the water. I accomplish this in a manner which will now be explained in some detail.

35 As may be seen from FIGURE 1, I use a plurality of stacked heat interchangers 36 positioned sequentially along the flow path of the flue gases. The heat interchangers are grouped into three stages. The first stage has four identical heat interchangers, 36A-36D; the second stage also has four identical heat interchangers 36E-36H; and the third stage has three heat interchangers 36I-36K.

40 The heat interchangers 36 comprise an upper band 38 and a lower band 40, these bands being interconnected by vanes 42. The upper band 38 is bonded to inner pipe 22 in a heat conducting manner, as by welding or brazing. The lower band 40 is in heat conducting relation with wall 33.

45 In one arrangement, lower band 40 is bonded to wall 33, while in another arrangement lower band 40 merely presses against wall 33. In the latter arrangement, an expansion opening 44 is used.

Operation

50 As the hot gases from burner 30 pass the first heat interchanger 36A, they heat vanes 42A. These conduct heat to upper band 38A and lower band 40A; these in turn heating walls 22 and 33 respectively. Each of these walls is in contact with water; so that the water in heated chamber 20 and in storage chamber 14 is heated simultaneously.

55 Since the hot flue gases heat the first heat interchanger 36A, it follows that the gases are cooled somewhat during this process. As a result, the flue gases are some-

what cooler when they reach an intermediate stage heat interchanger, such as 36E.

In order to compensate for the presence of the somewhat cooler flue gases surrounding it, heat interchanger 36E has more vanes than the first stage heat interchanger. This means that the intermediate stage heat interchanger 36E is slightly more efficient, but since it is in an atmosphere of cooler flue gases, the overall heat extraction is about the same as that of the first stage heat interchanger.

By the time the flue gases reach the third stage heat interchanger 36J, the gases are even cooler than previously. In accordance with my inventive concept, the heat interchanger 36J has more vanes than heat interchanger 36E.

In this way, heat interchanger 36J extracts substantially the same amount of heat, despite the fact that it is surrounded by relatively cool flue gases.

It is known that if the flue gases drop below the so-called "critical" temperature of about 90 degrees Fahrenheit, the moisture vapor contained therein tends to condense. The condensation absorbs chemicals from the flue gases, and forms corrosion producing deposits.

To avoid this possibility, the flue gases should not be cooled below 90 degrees Fahrenheit. The temperature of the exhaust may be readily controlled by using a predetermined number of heat interchangers having given number of vanes.

Since the final stage heat interchangers have the largest number of vanes, and therefore tend to introduce the largest impedance to the flow of the flue gases, it may be desirable at times, to have fewer heat interchangers in the final stage than in preceding stages.

In FIGURES 2-4, there are shown cross sectional views of heat interchangers that are typical of the three stages. As shown in FIGURE 2, the first stage heat interchanger 36B has an upper band 38B encircling inner pipe 22. Six vanes 42B connect the upper band 38B with lower band 40B, which is in contact with wall 33.

FIGURE 3 shows a second stage heat interchanger 36E. It comprises the same basic parts as the earlier stage heat interchanger, except that it has eight vanes 42E to extract heat from the cooler flue gases that surround it.

FIGURE 4 shows a still later stage heat interchanger 36J. It will be seen that this heat interchanger also contains the same basic parts as the others, except that it has twelve vanes 42. In this way, each heat interchanger extracts substantially the same amount of heat from the flue gases.

Heat interchangers 36 may be readily formed from flat sheet metal by a stamping operation. The trapezoidally shaped areas are first punched out, the bands and flanges are given the necessary angular relation, and the resultant stamping is then rolled to the desired conical form.

Variations

The three-stage heat exchanger 10 of FIGURE 1 has the advantage that each stage uses a number of identical heat interchangers 36.

Alternatively, instead of using stages, each successive heat interchanger may have progressively more vanes; or may have the same number of vanes, each having a slightly larger area. It may be desired, at times, to vary both the number and the size of the vanes in order to have equally overall-efficient heat extraction steps.

Under some conditions it may be desirable to transmit more heat to the heated chamber 20 than to the storage chamber 14. This result is readily achieved in any of a plurality of ways. For example, the widths of bands 38 and 40 can be adjusted, the heat conducting characteristics between walls 22 and 33 and the bands can be modified, and the shape of the vanes can be controlled. Any one or a combination of these parameters

can be used to selectively control the direction and amount of heat transmittal.

While the foregoing explanation has suggested that the lower bands 40 of the heat interchangers may be bonded to the inner surface of wall 33, this is not essential. In fact, an easy method of assembly and an improvement results if the bonding is omitted.

This assembly method merely requires that inner pipe 22 have the upper bands 38 of the heat interchangers fastened thereto. Then the entire assembly of pipe 22 and heat interchangers 36A-36K is inserted into pipe 33 until the exit opening of the heated chamber 20 coincides with the opening in wall 33. At this time the inlet opening of the heated chamber also coincides with the corresponding opening of wall 33.

The walls forming the common openings may then be sealed.

When using this arrangement, lower bands 40 are either opened wide initially, or expand when heated, in order to make good heat conducting contact with the inner surface of wall 33.

In the previously discussed embodiment where lower bands 40 are bonded to walls 33, heat losses occur when burner 30 is turned off. At that time the hot water in storage chamber 14 heats the lower bands 40, and these heat vanes 42. These vanes in turn heat the air in the now-unused heating chamber, and the heated air rises through the flue, to escape.

In the embodiment wherein lower bands 40 are not bonded to walls 33, these bands contract when the burner is turned off. The heat transmitting contact between lower bands 40 and walls 33 is thus broken, to obviate heating the air in the heating chamber. In this way, heat losses are minimized.

Heat transfers more efficiently to fluids in movement and to the lowest temperature fluid within a chamber. This structure utilizes these two natural laws by concentrating the greatest portion of heat onto the reduced amount of water in the inner chamber by use of vanes that direct their heat to the inner tube. When the heat is absorbed by the fluid, it expands, becomes lighter, moves upward within the inner chamber, and out into the storage chamber; whereas the heavier colder water moves into the inner chamber, thereby creating a self-induced rapid movement of the fluid. The incoming coldest temperature fluid is thus subjected to the greatest concentration of heat.

Advantages

My heat exchanger has several advantages over prior art devices.

It provides substantially equal heat extraction for each heat interchanger. The heat interchangers transmit heat in both directions to the storage chamber and the heated chamber. The amount of heat transmitted in each direction can be easily controlled. The individual heat interchangers are easily made. The heat absorbing areas have been greatly increased and therefore the overall length of the heat exchanger may be greatly decreased in length, and a long flue is no longer necessary. And finally, the unit is easily assembled.

It is understood that minor variation from the form of the invention disclosed herein may be made without departure from the spirit and scope of the invention, and that the specification and drawing are to be considered as merely illustrative rather than limiting.

I claim:

1. A heat exchanger comprising: three concentric enclosures, said first enclosure comprising a pipe that forms a heated chamber, the space between said first and second enclosures forming a heater chamber, and the space between said second and third enclosures forming a storage chamber, means for forming a passage between one end of said

heated chamber and one end of said storage chamber;
 means for forming a passage between the other end of said heated chamber and the other end of said storage chamber, whereby fluid may pass from said storage chamber into said heated chamber to be heated and may then pass from said heated chamber to said storage chamber to be stored until withdrawn;
 a plurality of heat interchangers, each having an inner band, an outer band, and generally radially extending vanes interconnecting said bands; the inner band of each interchanger being axially spaced relative to the outer band;
 means for positioning said heat interchangers in a stacked manner along the length of said heat exchanger with said inner bands in heat conducting relation with said inner enclosure, said outer bands in heat conducting relation with said second enclosure, and said vanes positioned in said heater chamber, the vanes of successive heat interchangers having progressively larger areas along substantially the entire length of said heater chamber, whereby successive vanes are enabled to more efficiently extract heat from the passing gases;
 and means for causing hot flue gases to traverse said heater chamber, and cause said vanes to extract heat from said flue gases and to transmit said heat to said heated chamber and said storage chamber.

2. A heat exchanger comprising:

three concentric enclosures, said first enclosure comprising an elongated pipe that forms a heated chamber, said second enclosure, comprising an elongated pipe that terminates in a flue, and said third enclosure comprising an envelope, the space between said first and second enclosures forming a heater chamber, and the space between said second and third enclosures forming a storage chamber;
 means for forming a passage between one end of said heated chamber and one end of said storage chamber; means for forming a passage between the other end of said heated chamber and the other end of said storage chamber, whereby fluid may pass from said storage chamber into said heated chamber to be heated, and may then pass from said heated chamber to said storage chamber to be stored until withdrawn;

a plurality of heat interchangers, each having an inner band, an outer band, and generally radially extending vanes interconnecting said bands; the inner band of each interchanger being axially spaced relative to the outer band;

means for positioning said heat interchangers in a stacked manner along the length of said heat exchanger with the inner surface of said inner band in heat conducting relation with the outer surface of said inner enclosure, said outer surface of said outer bands in heat conducting relation with the inner surface of second enclosure, and said vanes positioned in said heater chamber, the vanes of successive heat interchangers having progressively larger areas, whereby successive vanes are enabled to more efficiently extract heat from the passing gases;
 means for causing hot flue gases to traverse said heater chamber and said flue, and cause said vanes to extract heat from said flue gases and to transmit said heat to said heater chamber and said storage chamber;

means for introducing a fluid to be heated into said storage chamber;

and means for withdrawing heated fluid from said storage chamber.

3. The combination of claim 2 wherein said larger areas of said vanes comprise additional vanes.

4. The combination of claim 2 wherein said larger areas of said vanes comprise the same number of larger area vanes.
